UNITED STATES PATENT OFFICE.

HORACE J. FARRAR, OF SEATTLE, WASHINGTON, ASSIGNOR TO UNIVERSAL HIGH POWER TELEPHONE COMPANY, OF KING COUNTY, WASHINGTON.

SOUND AND LIGHT AMPLIFIER.

1,156,865.

Specification of Letters Patent.

Patented Oct. 12, 1915.

Application filed January 27, 1914. Serial No. 814,845.

To all whom it may concern:

Be it known that I, HORACE J. FARRAR, a citizen of the United States, and a resident of the city of Seattle, county of King, and 5 State of Washington, have invented certain new and useful Improvements in Sound and Light Amplifiers, of which the following is a specification.

This invention relates to sound and light 10 amplifiers and has for its principal object to provide an article of this character which is of unique and compact construction, as well as sightly in appearance, and by means of which sound when transmitted to the device 15 may be amplified, together with the light, from an ordinary electric light bulb, through a common amplifying device, advantage being taken of the assistance which a shaft of light affords to the transmission of sound. 20 The invention will be more fully described in the following specification, illustrated in the accompanying drawings and pointed out in the appended claim.

In the drawings, Figure 1 is a side elevation 25 of my device, partly in section. Fig. 2 is a fragmentary enlarged detailed view of the same.

Referring now more particularly to the 30 drawings, reference numeral 1 designates a cylindrical casing whose top is closed and has projecting upwardly from it a suitable ring, such as indicated at 2, and to which is secured one end of a supporting cord or other such flexible member 3, the other end 35 of the same being secured to the ceiling of a room 4. The lower end of the casing 1 is screw-threaded, as shown, to receive similar threads upon the circular casting 5 which is screw-threaded to a disk 6, through which 40 pass the ends 7 of an electro magnet. Secured to the bottom edge of the said casting, by means of screw threads as shown, is a second circular casting 8 which has a suitable annular recess within which are insulating rings 9 and 10, and between which is 45 confined a diaphragm 11, the said insulating rings and diaphragm being held in place by means of a plate 12 screw-threaded to the lower circular edge of the casting 8 as is best 50 seen in Fig. 2.

The disk 12 is centrally apertured as seen at 13 and the aperture is skirted by a tubular projection 14, which is externally threaded as shown. Screw-threaded to the said 55 tubular projection is the smaller end of a

horn-like member 15, through the larger end of which passes suitable binding screws, such as indicated at 16, by means of which a flaring reflector 17 is secured to the member 15. 60

18 is an ordinary electric light bulb and 19 its socket, the latter having extending radially from it arms 20, whose outer ends are secured to the inner surface of the member 15, and projecting upwardly from the 65 said socket is a cone 21.

Secured to each side of the device is a conduit 22.

23 indicates a source of electrical energy 70 from which extends a wire 24 which extends to a switch 25, thence upwardly and to the left, as viewed in Fig. 1, to the top of the casing 1 whereinto it passes and is coiled around the magnet 7 and finally passes out of the said casing and back to its source. 75 Extending from the same source is a wire 26 which extends to a switch 27, thence upwardly and to one of the conduits 22, through which it passes, thence to the light bulb 18, upwardly through the other conduit 22 and finally to its source 23. 80

It will be noted that the diaphragm 11 is of unusual relative diameter, it being understood that the transmitter, indicated at 28, is of some suitable amplifying construction, such for example as that shown in Patent Number 766821 of Gamache. The diaphragm 11 is caused to vibrate by the intermittent opening and closing of the circuit and the resultant energizing and deenergizing of the magnet 7. The sound will be further amplified by the flaring member 15 and the light reflector 17, and when the light circuit is closed advantage is had of the shaft of light which proceeds downwardly 90 from the reflector 17. In practice I prefer to suspend one of the devices above a table such as is used in cafés and the like, and so long as sound is transmitted to the diaphragm 11 from a phonograph or the like, and the switch 25 is open, such sound will be conducted to and amplified just above the heads of the persons seated at the table and when such persons no longer desire to hear such sounds the same may be discontinued 95 by turning the switch 25. 100

I have shown a particular form of embodiment of my invention but am aware that many changes therein will readily suggest themselves to others skilled in the art, 110

without departing from the spirit and scope of my invention and I therefore desire to avoid being limited to the exact form described except as limited by the appended 5 claim.

What I claim as new is—

In a combined light and sound device, the combination of a hollow circular member having its lower end internally threaded and 10 which is adapted to contain the receiving end of a telephone, means for suspending the said member to a ceiling, a circular plate having a threaded periphery by means of which the plate is removably attached to 15 the said circular member, the said plate being provided with an aperture through its center, a hornlike member and means for removably securing its smaller end to the

said plate so that the aperture in the plate communicates with the interior of the hornlike member, means on the lower edge of the said hornlike member for removably securing a lamp shade thereto, arms extending across the bottom of the hornlike member, a light socket supported by means of 25 the said arms, a cone shaped member mounted above the said socket and whose base is of about the same diameter as that of the socket, the said arms supporting both the socket and the cone, and the apex of the said 30 cone being pointed toward the source of sound.

HORACE J. FARRAR.
